UNITED STATES PATENT OFFICE.

DICIE CROAN, OF RIVER VIEW, KENTUCKY.

COMPOUND FOR CHICKEN-CHOLERA.

SPECIFICATION forming part of Letters Patent No. 243,693, dated July 5, 1881.

Application filed April 16, 1881. (Specimens.)

To all whom it may concern:

Be it known that I, DICIE CROAN, of River View, in the county of Jefferson and State of Kentucky, have invented certain new and useful Improvements in Medical Compounds; and I do hereby declare that the following is a full, clear, and exact description of the invention, which will enable others skilled in the art to which it appertains to make and use the same.

10 This invention relates to a medical compound for the cure of chicken-cholera; and it consists of the compounding of certain ingredients, substantially as hereinafter more fully set forth.

15 The ingredients are as follows: red-oak bark, two pounds; poke-root, two pounds; wahoo-root, one pound; *Euphorbia maculata*, or garden-spurge, one pound; black mustard-seed, one table-spoonful; water, pure, three gallons.

20 Place these in a boiler and boil down to one gallon in quantity.

Directions: Place the compound, in suitable quantities, in a trough or basin for the fowls—those not too far overcome—to drink, which 25 they will do freely. The better form to give it in is by placing it in buttermilk or mixing it with meal or bran. If they are too far overcome to be able to eat or drink, administer about one gill of the compound three times a 30 day, mixing it with meal and forcing it with the finger down the throat, and drenching

with the liquid. Generally fowls thus treated will be able to eat voluntarily the second day.

This compound is a powerful stimulant and astringent, checks the bowels, arouses the action of the vital forces, equalizes the circulation of the blood, and imparts with rapidity new life to the diseased fowls.

If the compound be set out occasionally—say once a month—the trouble of forced administrations will be avoided.

The aforesaid ingredients are readily obtained and in abundant quantities in almost every rural locality or upon every plantation, and are almost all well known for their medical qualities.

Having thus described my invention, I claim and desire to secure by Letters Patent—

The described medical compound, compounded in about the proportions and manner stated, 50 consisting of red-oak bark, poke-root, wahoo-root, *Euphorbia maculata*, or garden-spurge, and black mustard-seed, substantially as set forth.

In testimony that I claim the foregoing as 55 my own I have hereto affixed my signature in presence of two witnesses.

DICIE CROAN.

Witnesses:

D. T. HAYDEN,
A. P. STEELE.
